UNITED STATES PATENT OFFICE.

JOHN J. BRADFIELD, OF JAMAICA, NEW YORK.

FASTENER AND GUIDE FOR ASPHALT SHINGLES.

Application filed July 29, 1924. Serial No. 728,947.

To all whom it may concern:

Be it known that I, JOHN J. BRADFIELD, a citizen of the United States, and a resident of the city of New York, Jamaica, borough 5 of Queens, in the county of Queens and State of New York, have invented a new and Improved Fastener and Guide for Asphalt Shingles, of which the following is a full, clear, and exact description.

10 This invention relates to fastening means for securing asphalt shingles on roofs and has for an object to provide an improved construction which will not only act as fastening means but will act as guiding 15 means for correctly aligning the shingles.

Another object of the invention is to provide a fastening device which acts at the same time on a plurality of overlapped shingles for holding the same in place.

20 Another object, more specifically, is to provide a guide and fastening device for asphalt shingles wherein the device may be applied to one shingle and caused to act on the next superimposed shingle for aligning the two shingles and those arranged 25 adjacent thereto.

In the accompanying drawing—

Figure 1 is a plan view of part of a roof supplied with asphalt shingles and combined fastener and guide embodying the invention.

Figure 2 is a plan view of the fastener and guide shown in Figure 1, the same being on an enlarged scale.

30 Figure 3 is an edge view of the structure shown in Figure 2.

Figure 4 is a detail fragmentary sectional view through Figure 1, approximately on line 4—4.

40 Figure 5 is a detail fragmentary sectional view through Figure 1, approximately on line 5—5.

Referring to the accompanying drawing by numerals, 1 indicates a fastener and 45 guide and 2 an asphalt shingle. As indicated in Figure 1, a number of shingles have been applied to a roof, said shingles being of identical construction and supplied with identically formed fastener members and 50 guides 1. Each of these fastening members and guides is formed as shown in Figures 2 and 3.

Referring to these figures, it will be noted that flat end sections 3 and 4 are 55 provided for each fastener and a centrally raised section 5 which is provided with a

plurality of pressed out spurs 6. These spurs extend downwardly as shown in Figure 3 so as to engage the turned over end 7 of the shingle 2. The flat sections 3 and 4 are provided with pressed out spurs 8 which are adapted to be forced through the shingle 2 and clinched on the opposite side so as to positively connect the fastener with the shingle as illustrated in Figure 5. As illustrated more particularly in Figure 4, each of the shingles 2 is provided with a turned over end 7 which is forced under the pressed up portion 5, after which, this pressed up portion is forced down again 70 until the parts are closely associated together as shown in Figure 4 wherein the spur 6 will be projecting into the end 9.

In forming the pressed out portion 5, the same is provided with inclined shoulders 10 and 11 which are at right angles to each other whereby they will act as guides as well as supports for adjacent shingles. For instance, when the shingle 2' is placed in position, side shingles 2" are placed as shown 80 in Figure 1 so that their edges will engage the shoulders 10 and 11. The shingle 2 will then be placed in position but before this is done suitable nails 12 are forced through the corners of the shingles 2" and also through part of the shingle 2'. By reason of this construction, the various shingles are held in place at their lower ends by the bent over portion 9 interlocking with the fastener 1 while the upper part of each shingle is 90 fastened by at least two nails and both nails and the fastener are covered by the superimposed shingle.

Heretofore, when placing asphalt shingles on a roof, it was necessary to provide vertical lines on the roof properly spaced apart so as to align the shingles correctly. According to the present invention, the shoulders 10 and 11 will cause a proper alignment of the respective shingles and, consequently, after the first row of shingles at the lower edge of the roof have been placed in position, the others will automatically assume the correct aligning position. This feature will permit not only a satisfactory fastening of the shingles but permit the workmen to place more shingles in position in a given time than if extra care was necessary to keep the shingles properly aligned and extra time necessary to provide guiding lines for the shingles.

What I claim is:

1. An artificial shingle, comprising an as-

- phalt shingle body and a fastener and guide positioned on said body near one corner thereof, said fastener and guide comprising a strip of metal having a central pressed out portion for receiving the end of a superimposed shingle body, and spurs at each end adapted to extend through and be clinched on the opposite face of the first mentioned shingle body.
10. 2. A combined shingle fastener and guide, comprising a rectangular shingle body, and a strip of metal permanently secured to said body near one corner, said strip of metal having spurs pressed from the end portions extending through the body and clinched, said strip of metal also having a central pressed up portion provided with shoulders parallel to the nearest edges of said body, and with downwardly extending spurs for engagement with the end of a superimposed shingle adapted to be applied to the fastener.
15. 3. A combined shingle and fastener, comprising a rectangular shingle body and a strip of metal permanently secured to said body near one corner, said strip of metal having spurs pressed from the end portions extending through the shingle body and clinched, said strip of metal also having a central pressed up portion provided with shoulders parallel to the nearest edges of said body for guiding and retaining the corner of the superimposed shingle.

JOHN J. BRADFIELD.
